A. E. MAYNARD,
GRINDING MACHINE,
APPLICATION FILED MAY 10, 1920.

1,397,289.

Patented Nov. 15, 1921.

UNITED STATES PATENT OFFICE.

ALBERT E. MAYNARD, OF SOUTHERIDGE, MASSACHUSETTS, ASSIGNOR TO AMERICAN OPTICAL COMPANY, OF SOUTHERIDGE, MASSACHUSETTS, A VOLUNTARY ASSOCIATION OF MASSACHUSETTS.

GRINDING-MACHINE.

1,397,289.

Specification of Letters Patent.

Patented Nov. 15, 1921.

Application filed May 10, 1920. Serial No. 380,303.

To all whom it may concern:

Be it known that I, ALBERT E. MAYNARD, a citizen of the United States, residing at Southbridge, in the county of Worcester and 5 State of Massachusetts, have invented certain new and useful Improvements in Grinding-Machines, of which the following is a specification.

This invention relates to improvements in 10 grinding machines and has particular reference to a novel and improved device for use in connection with machines for the grinding of ophthalmic or similar lenses.

The principal object of the present invention 15 is the provision of a novel and improved structure satisfactorily applicable to existing types of lens grinding machines, which will adapt said machines to properly receive and operatively secure in position tools of 20 types other than those designed for the particular machine.

A further object of the present invention 25 is the provision of a device of this character which may be readily adjusted to receive different sizes of tools and will securely retain the same in central position.

A further object of the present invention 30 is the provision of an improved clamping or retaining device for lens grinding tools, lens holders or the like, which shall serve to automatically center the tool to properly position the same to prevent movement thereof in any direction and at the same time have the axis, in the case of a cylinder tool, properly held and disposed with respect to the holding device.

Other objects and advantages of my improved construction should be readily apparent by reference to the following specification 40 taken in connection with the accompanying drawings, and it will be understood that I may make any modifications in the specific details of construction shown and described within the scope of the appended 45 claims without departing from or exceeding the spirit of my invention.

Figure I represents a side elevation of a structure embodying my improvements.

Fig. II represents a top plan view thereof.

50 Fig. III represents a similar view with the tool removed.

Fig. IV represents a longitudinal sectional view taken as on the line IV—IV of Fig. III.

Fig. V represents a bottom plan view of the grinding tool. 55

Fig. VI represents a perspective view of the clamp operating wrench.

In the drawings, the numeral 1 designates the base portion of the holder, which is provided with a socket to receive the stud 2 on 60 the table portion 3 of the clamp. This table portion 3 is provided with the laterally up-standing guide flanges 4 which serve as rests for the under side of the lens holder or grinding member 5, and at the same time 65 provide guide ways between which slide the protecting plates 6 of the adjustable end clamp blocks 7. These clamp blocks have the stud sleeves 8 sliding in recesses 9 in the table portion 3, said sleeves being internally 70 threaded to receive the right and left hand adjusting or clamp screw 10 which is threaded into said sleeves and passes through the central portion of the table 3. A positioning plate 11 secured to the upper face of 75 the table has a depending yoke 12 fitting within a groove 13 in the adjusting screw 10, serving to hold this member against longitudinal movement within the table while permitting of its free rotation to shift the 80 clamp blocks 6 and 7 in and out, as may be desired. Guides 14 sliding in sockets 15 in the table 3 aid in steadyng the clamp blocks and preventing twisting movement thereof during the adjustment. 85

In this connection I would call particular attention to the shape of the plate 11, which is widest at its center, as at the point marked 16, and tapers toward both ends. This plate is adapted to fit within the supposedly rectangular socket 17 milled or otherwise suitably formed in the under face of the member 5, and it is on this account that it is provided with the pieces tapering toward the end. This is due to the fact that the recess 95 is not always exactly correctly positioned in the tool so that were the plate of size to substantially fit the tool socket 17 there might be possibility of the tool being held in slightly twisted position. With my improved taper shape, however, the width at the point 16 is substantially the width of the groove or socket 17 so that the tool is properly positioned lengthwise and is absolutely held against any accidental lengthwise movement while the clamp blocks 7 are brought 100 105

inward toward each other simultaneously, and as their jaw portions 18 engage the tool 5 adjacent its corners they serve to automatically position the tool according to its side 5 faces rocking it if need be about the points 16 to effect the desired transverse shifting thereof. To facilitate most secure retaining of the tool in position the jaws 18 are slightly under-cut so that they engage at the upper 10 edge first tending to draw the block downward in engagement with the base portion rather than to press it upward therefrom as might be the case were straight face jaws employed.

15 In connection with the construction of my improved device I would call particular attention to the plate portions 6 overlying the joint between the main table portion and the terminal clamps and also to the sleeve 8 fitting within the socket 9 of the table portion, in that these parts combined provide an extremely tight and satisfactory joint preventing entry of excess of abrasive or the like liable to cause undue wear of the parts, insuring the parts at all times operating easily 20 and freely and securely holding the parts in desired adjusted position, and reducing to a minimum the liability of said parts to either become stuck or unduly worn on account of 25 excess of abrasive thereto.

30 To rotate the screw 10 and move the jaws into or out of clamping position I preferably form in the ends of the screw slots 20 adapted to receive the flattened web 19 of the 35 wrench member 21 having a handle 22 for rotating. It will thus be seen that the wrench may be inserted at either end of the tool to securely tighten the jaws or to release them, as desired, and may be easily withdrawn to 40 be out of the way while the device is in operation.

I claim:

1. In a device of the character described, the combination with a table portion having 45 a central positioning plate tapering toward the ends of a pair of slidably end members carried by the table and disposed in the direction of the ends of the central positioning member, said end members each being provided with a pair of clamp jaws located 50 respectively on opposite sides of the line of the central positioning member whereby said central positioning member will serve to centrally position a lens tool while the 55 tapered formation will permit of the clamp jaw twisting it about the guide member to insure proper positioning of the tool as respects the table member.

2. A device of the character described, 60 comprising a table portion having a central positioning member to control the lateral positioning of a lens block and having a pair of clamp portions each provided with spaced clamping jaws and means for shifting the clamping jaws toward or away from 65

each other whereby the spaced relationship of said parts serves to adjust and position a lens tool about the fixed central positioning member.

3. A device of the character described, 70 comprising a table portion having a transverse aperture formed therethrough and a pair of clamp members each having a guide sleeve portion engaged in the aperture, supplemental interlocking guides between the 75 clamp members and table portion for preventing relative twisting movement thereof, and a single means engaging both of the sleeve members for simultaneously shifting them toward or away from each other as 80 desired.

4. The combination with a tool having a socket in the under face thereof, of a holder for the tool having a table portion provided with a positioning member centrally of the 85 same width as the socket and terminally of less width than the width of the socket and clamp members carried by the table for engagement with the tool to secure the latter 90 in position.

5. An attachment for a grinding machine comprising a table having a depending attachment stud and an upwardly projecting positioning plate, a pair of clamping plates carried by the table and terminating in upwardly projecting clamping jaws, means for simultaneously shifting the jaws into or out of operative position, and means on the positioning plate for preventing movement of both jaws in the same 100 direction.

6. In a device of the character described, the combination with a table portion, of a guide plate thereon, a right and left hand adjusting screw journaled in the table, 105 means on the guide plate engaging the screw for preventing longitudinal movement thereof, and clamp jaws carried by the table and each having a portion engaged by the adjusting screw whereby the clamp jaws 110 are simultaneously adjusted toward or away from each other by rotating movement of the screw.

7. A device of the character described, 115 comprising a table portion having a transverse aperture formed therethrough and a pair of clamp members each having a guide sleeve portion engaged in the aperture, supplemental interlocking guides between the 120 clamp members and table portion for preventing relative twisting movement thereof, and a single means engaging both of the sleeve members for simultaneously shifting them toward or away from each other as desired, said means including a right and 125 left hand screw having a central peripheral groove, and means carried by the table and engaged in the groove for preventing longitudinal shifting movement of the screw.

8. A device of the character described, 130

comprising a table portion having a transverse aperture formed therethrough and a pair of clamp members each having a guide sleeve portion engaged in the aperture, supplemental interlocking guides between the clamp members and table portion for preventing relative twisting movement thereof, and a single means engaging both of the sleeve members for simultaneously shifting them toward or away from each other as desired, said means including a right and left hand screw having a central peripheral groove, and means carried by the table and

engaged in the groove for preventing longitudinal shifting movement of the screw, 15 said means having a plate portion resting on and secured to the upper face of the table member to form a lens tool centering guide.

In testimony whereof I have affixed my 20 signature, in presence of two witnesses.

ALBERT E. MAYNARD.
